UNITED STATES PATENT OFFICE.

JOHN BARTA, OF CHICAGO, ILLINOIS.

CHAIR.

No. 840,463.

Specification of Letters Patent.

Patented Jan. 8, 1907.

Application filed July 26, 1904. Serial No. 218,220.

To all whom it may concern:

Be it known that I, JOHN BARTA, a citizen of the United States, residing at Chicago, in the county of Cook and State of Illinois, have invented a new and useful Improvement in Chairs, of which the following is a specification.

This invention relates generally to chairs, and more particularly to an improved construction of metal chair, the object being to provide an exceedingly cheap and simple construction of metal chair which shall be light, at the same time strong and durable; and another object of the invention is to provide a metal chair which can be folded into compact form when not in use.

With these various objects in view the invention consists in the novel features of construction and combination hereinafter fully described, and pointed out in the claims.

In the drawings forming a part of this specification, Figure 1 is a perspective view of metal chair constructed in accordance with my invention. Fig. 2 is an elevation of the same in a folded position. Fig. 3 is a detail sectional view taken through the seat-frame, showing the means for locking the chair in its opened position. Fig. 4 is a detail perspective view showing the manner of connecting the braces to the rear legs. Figs. 5 and 6 are detail views showing the manner of connecting the upper ends of the front legs to the seat-frame.

In constructing a chair in accordance with my invention I preferably employ two pieces of angle-iron A of suitable weight and thickness and from which I make the rear standards of the chair, the flanges of the angle-iron being headed down at both ends, as shown at A' and A'', in order to provide flat foot portions for the rear legs and also suitable finish for the top portions of the rear standards or back-sections. The back consists of the top cross-piece B and the bottom cross-piece C and the connecting-strips D, all of said parts being made of thin metal. The seat-frame E is made of angle-iron and is hinged to the inner faces and standards A, as shown at E'. The seat proper, F, is preferably made of leather and is supported upon coil-springs G, connected at their outer ends to the seat-frame and at their inner ends to a metallic plate G, which rests directly beneath the center of the seat, as most clearly shown in Figs. 2 and 3. The front legs H are also made of angle-iron, the flanges being turned up at

their lower ends, as shown at H', in order to provide suitable foot portions for said legs. The legs are pivotally connected at their upper ends to the exterior of the chair-frame, as shown at H'', and the forward flange of the leg is slotted, as shown at H', to receive the vertical flange of the seat-frame when the leg is set up to support the said seat-frame, and the upper end of the forward flange of which leg is turned down, as shown at H'', and is adapted to engage the under side of the horizontal flange and the seat-frame, as most clearly shown in Fig. 5, thereby relieving the pivot of a great deal of strain and providing a steady connection when the chair is opened, as shown in Fig. 1.

The front legs are connected by means of a horizontal brace I, and the rear legs of the standards are connected by means of horizontal brace K, and a latch L is pivotally connected to this brace K and is adapted to be turned up and engage the rear portion of the seat-frame when the chair is opened and which will prevent the chair being accidentally folded. The front and rear legs are braced by means of brace-bars M, pivoted at M' to the exterior of the front legs and bent at their rear ends, as shown at M'', and adapted to engage the cleats M', secured upon the rear flanges of the rear standards A. When the chair is set up, as shown in Fig. 1, all of the parts are thoroughly braced, and a steady well-balanced chair is provided, being constructed of thin angle-iron, and an exceedingly light and durable chair can be constructed. When it is desired to fold the chair, the braces M are disengaged from the cleats M' and the latch L is turned down, so as to disengage the seat-frame. The braces M are then turned down in line with the front legs, and the seat-frame is pushed upwardly and rearwardly until it fits between the flanges of the rear standards. The front legs will overlap the bottom of the seat-frame, as most clearly shown in Fig. 2, and when the chair has been thus folded it will occupy very little space.

Having thus fully described my invention, what I claim as new, and desire to secure by Letters Patent, is—

1. A folding chair comprising legs formed of angle-irons, a seat pivotally connecting the front and rear legs of said chair, cleats secured to the flange of the rear legs and braces pivoted to the front legs having angled ends adapted to fit over the cleats of the

rear legs and lock the legs in a vertical position, for the purpose described.

2. A metal chair comprising the rear standards of angle-iron connected by the top and bottom portions of the back and also by means of a horizontal brace, a seat-frame also of angle-iron pivotally connected to the rear standards, the front legs of angle-iron slotted and shouldered at their upper ends 10 and pivotally connected to the seat-frame, the braces pivotally connected to the front

legs and the cleats arranged upon the rear standards and adapted to be engaged by the ends of the pivot-brace, and a latch pivoted to the horizontal brace connecting the rear 15 standards and adapted to engage the seat-frame when in a horizontal position.
